ATTORNEY S

UNITED STATES PATENT OFFICE.

HENRY H. THORP, OF CLEVELAND, OHIO.

DESIGN FOR A FONT OF PRINTING-TYPE.

SPECIFICATION forming part of Design No. 13,279, dated August 29, 1882.

Application filed July 27, 1882. Term of patent 14 years.

To all whom it may concern:

Be it known that I, HENRY H. THORP, of the city of Cleveland, in the county of Cuyahoga and State of Ohio, have produced a new and original Design for a Font of Printing-
Types, of which the accompanying specimen or impression is an exact representation, and is made a part of this specification.

What I claim as my invention, and desire to secure by Letters Patent, is—
The design herein set forth for a font of printing-types.

HENRY H. THORP.
